AUTOMATIC CIRCUIT BREAKER
RETARDING MECHANISMDavid C. Hubbard, Centralia, Mo., assignor to
A. B. Chance Company, Centralia, Mo., a corporation of Missouri

Application April 10, 1947, Serial No. 740,687

12 Claims. (Cl. 200—97)

1

The present invention relates to automatic circuit recloser mechanism, and is particularly concerned with circuit makers and breakers of the type which are adapted to be immersed in an insulating liquid, such as oil.

One of the objects of the invention is the provision of an improved circuit maker and breaker of the overload type which is provided with automatic reclosing mechanism adapted to provide for a fast opening of the circuit on the first and second operations in the event of an overload, and for the time delay opening of the circuit on the third and fourth operations, after which the circuit breaker is held in open position and can only be closed by means of a manual operation.

Another object of the invention is the provision of an improved circuit maker and breaker of the class described which is adapted to clear automatically all temporary line faults which include the majority of line disturbances, thus increasing service continuity and reducing the areas which are cut out to the smallest possible size.

Another object of the invention is the provision of an improved automatic circuit breaker and recloser which is adapted to prevent the burning of contact surfaces by high speed opening and high speed closing, which is sturdy in construction, capable of economical manufacture, and adapted to be used for a long period of time without necessity for repair or replacement.

A further object of the invention is the provision of an automatic circuit breaker and recloser in which each break of the contacts is not accomplished until a full measure of oil has been forced into a metering cylinder which progresses a predetermined amount in its travel during the first and second operations; which is adapted to eject oil across the contacts in such manner as to aid in breaking the arc; which provides a time delay without effecting any delay during the instant while the contacts are being made or broken; and which utilizes a small amount of the travel of the delaying mechanism for dampening the shock of its travel.

Still a further object of the invention is the provision of an improved circuit breaker and automatic recloser which provides additional time delay in the event of heavier currents before the device recloses the contacts in order to allow more time for the oil about the contacts to clear itself of gas and of carbon particles.

Another object is the provision of an improved device of the class described which provides a predetermined minimum time delay on reclosing of the circuit under ordinary conditions, and an

additional time delay is provided before reclosing when the device has interrupted heavier current.

Another object of the invention is the provision of a device of the class described which is adapted to provide a proper time delay before the contacts move to break the circuit, but which is also adapted to permit the parts to move thereafter at such a speed that they are adapted to eject oil across the path of the arc in order to break the arc and protect the contents.

Another object of the invention is the provision of an improved device of the class described which may be provided with a suitable lock-out mechanism for preventing the recloser from resetting the contacts so that it is necessary to reset them manually after the third or fourth operation, and in which the time delay mechanism itself is locked against return after the third or fourth operation, so that after a prolonged outage, consumer equipment which is connected to the line in the "on" position will not be the cause of another instantaneous operation of the breaker, which will not occur when the time delay is also locked out in its third or fourth position.

To summarize briefly the most important features of the present invention, it is a further object of the invention to provide an automatic circuit recloser mechanism which has all of the advantages of the devices of the prior art, and which is also characterized by the following features: (1) constant measure of oil, independent of piston travel, for moving a time delay piston; (2) release of time delay pressure from the armature at the instant of contact break to allow the full force of the dash pot piston to eject oil across the resultant arc path; (3) cushion the rest of the piston travel; (4) ejection of oil across the arc path; (5) lock-out of the time delay mechanism in a time delay position to provide a time delay upon reclosing in order to prevent the opening of the contacts by the surge of starting current which might be required by consumer equipment which has been connected to the line in the "on" position during a prolonged outage.

Other objects and advantages of the invention will be apparent from the following description and the accompanying drawings, in which similar characters of reference indicate similar parts throughout the several views.

Referring to the two sheets of drawings,

Fig. 1 is a fragmentary axial sectional view taken through an automatic recloser mechanism embodying the invention, on a plane passing through the axis of the coils and pistons.

them manually after the third or fourth operation, and in which the time delay mechanism itself is locked against return after the third or fourth operation, so that after a prolonged outage, consumer equipment which is connected to the line in the "on" position will not be the cause of another instantaneous operation of the breaker, which will not occur when the time delay is also locked out in its third or fourth position.

Other objects and advantages of the invention will be apparent from the following description and the accompanying drawings, in which similar characters of reference indicate similar parts throughout the several views.

ing details of structure of the snap contact mechanism.

Fig. 3 is a fragmentary view similar to Fig. 1, showing a modification in which the solenoid coil is lowermost and the dash pot located above it to permit the interchange of coils of different characteristics for changing the recloser rating.

The present circuit interrupter and recloser mechanism is intended to be submerged in an enclosed tank in oil, the leads being brought out the top of the tank through elongated multi-skirt insulators, the tank being grounded, and separate lightning arresters being provided between the ground of the tank and the conductor at the end of each insulator.

The present device preferably includes a supporting spool 10 for an overload coil 11, the spool having a central bore 12 for receiving the substantially cylindrical armature 13. The assembly is carried by the cover of the enclosing tank, from which it depends. The spool 10 supports at its lower end a housing member 14 which includes a cylinder 15 having an inner cylindrical chamber 16 serving as a dash pot.

The dash pot piston 17 may comprise a disk 18 having a suitable clearance with respect to the cylindrical wall 16, and having a hub 19 with a bore 20 for receiving the armature 13 to which it is riveted by the rivet 21. Radial reinforcing flanges 22 connect the disk 18 with the hub 19, and two of such radial reinforcing flanges are extended to form fins 23 which project laterally from two slots 24 in the cylinder wall 15 for supporting a pair of snap springs 25 by means of which the movable contacts are actuated.

The housing 14 also includes a laterally extending, U-shaped portion 26 comprising a pair of parallel walls 27, 28, and the end wall 29. This U-shaped portion may be open at its top and bottom for access of oil to the contacts. The left wall 30, between this U-shaped portion and the cylinder 15, may be thickened toward the top to provide a diagonally and upwardly extending stop surface 31 for limiting the motion of the switch arm. The lower portion of this wall supports a pair of pivot flanges 32 separated by a slot 33 for receiving the switch arm 34, which preferably consists of an insulating shield.

The switch arm or shield 34 may consist of a laminated member of indurated fiber which is impregnated with a phenolic condensation compound, and which may be a sector, being provided at its axis with an aperture 35 for receiving the rivet or pintle 36 by means of which it is pivoted between the flanges 32.

The contact arm 34 supports adjacent its upper edge 37 a bridging contact 38 (Fig. 2) which may consist of an elongated cylindrical member having enlarged threaded portions 39 which pass through an aperture 40 in the shield 34 to which they are secured by nuts 41. The projecting cylindrical portions 42 of this bridging contact are adapted to engage the fixed contacts 44, 44 which are insulated from and supported by the parallel side walls 27, 28 of the U-shaped portion 26 of housing 14.

Fixed contacts 44, 44 preferably have partially cylindrical socket formations 45 for receiving the cylindrical portions 42 of the bridging contact 38 and for limiting the downward motion of the bridging contact 38 and switch arm 34. The contacts 44, 44 are connected to suitable connectors 46 for receiving conductors which connect the switch in a circuit.

At a point between the axis of the switch arm sector 34 and its periphery 47 this switch arm is

provided with a transversely extending spring supporting post 48. Such a post may be secured to the insulating sector 34 in the same manner as the contact 38, and the post is preferably provided with a pair of peripheral grooves 49, one adjacent each end, for receiving a loop 50 carried by the end of each spring 25. The other end of each spring 25 has its loop hooked through an aperture 51 in the fins 23 carried by dash pot piston 17.

Various forms of switch mechanism may be employed, and the one which has been selected to illustrate the invention is merely one of the forms which I contemplate using.

15 The U-shaped housing portion 26 may have its side walls 27, 28 each provided with an oval aperture 52 extending upwardly from the location of the fixed contacts 44, 44 so that the oil which is projected toward the contacts may pass outwardly toward the right and left through these apertures.

20 The operation of the switch mechanism is as follows: When the shield 34 is in the position of Fig. 1, the fins 23 being below the pivot 36 of the shield 34, springs 25 pull the shield 34 downwardly so that the contact 38 engages fixed contacts 44, 44.

25 As the dash pot 17 moves upwardly, the fins 23 carry the left end of the springs 25 upwardly, and when the fins 23 pass the line of centers of post 48, pivot 36, and spring attachment 51, the spring 25 thereafter pulls upwardly on the shield 34, which snaps upward, breaking the circuit between contact 38 and contacts 44, 44. The shield 34 is then interposed between the fixed contacts 44, 44, and it continues upward until it leaves the dotted line position shown in Fig. 1, engaging the stop surface 31.

30 Upon the return movement of the dash pot piston 17, the closing of the switch is again accomplished with a snap action, and the springs 25 tend to hold the switch closed or open, depending upon the position in which they happen to be.

35 The piston 18 has a suitable clearance with respect to the cylinder bore 16 so that a predetermined amount of oil may escape around the edges of the piston 17 to permit the armature 13 to move at a regulated velocity.

40 The piston 18 has a suitable clearance with respect to the cylinder bore 16 so that a predetermined amount of oil may escape around the edges of the piston 17 to permit the armature 13 to move at a regulated velocity.

45 While the piston 17 is moving along the slots 24, oil is projected through these slots toward the contacts of the switch to assist in quenching the arc. The slots 24 terminate short of the end of the piston bore 16 so that after the piston passes the end of the slots 24 the escape of oil from the space above the piston is greatly diminished as it is limited to the oil which escapes between the edges of the piston and the wall of the bore 16. Thus the upper end of the cylinder is utilized for cushioning the shock of movement of the piston, armature, and associated parts. These parts are also brought to a quick stop.

50 The armature 13 is carried at its upper end by an extension rod 53, which also serves to support a plurality of valve members. Rod 53 is mounted in a cylindrical socket 54 in the armature 13 and secured by a transverse rivet 55.

55 Above the armature 13 the rod 53 supports an oil pumping bushing 56 which has a sliding fit in a tubular lining 57 located inside spool 10. The oil pumping bushing 56 is secured to rod 53 by means of a transverse rivet 58, and it is provided at its upper end with a plane surface

59 serving as a cut-off valve with respect to the transverse conduit or port 60.

The upper casting 61 comprises a metal member provided with a tubular portion 62 having its end wall 63 provided with a cylindrical bore 64. The bore 64 has a sliding fit with a cylindrical portion 65 on the rod 53; and the rod has an upwardly tapered portion 66 which ends in an abrupt shoulder 67 above, and tapers to the size of the cylindrical portion of rod 53 at the point 68. The location of these parts is such that when the shoulder 59 closes the port 60, the shoulder 67 passes the upper surface 69 on the tubular housing 61 and permits the escape of oil around the tapered portion 66 of extension rod 53.

The upper housing 61 is provided with a lateral tubular extension 70 which contains the conduit 60; and may terminate in a threaded bore 71 closed by a screw plug 72. This bore may serve as a clean-out opening by removal of the screw plug 72.

Bore 60 communicates with a downwardly extending port 73 which is closed by a ball valve 74 which permits oil to enter the port 73 but prevents its exit. A pin 75 above the ball valve 74 prevents the ball 74 from leaving its seat, except for a predetermined movement. The conduit 60 also communicates with an upwardly extending bore 75 which is closed by a gravity actuated ball valve 77, also having a pin 78 to limit its upward movement.

Tubular extension 70 is provided with a circular plate 79 on its upper side, to which is attached another cylinder 80 by means of screw bolts 81. The cylinder 80 has an inner cylindrical wall 82 for engagement with a piston 83 carried by a piston rod 84. The wall of cylinder 80 has an enlarged outlet bore 85 located at a point just below the dash line 86, which indicates the second position of this piston. The dot line 87 below the enlarged outlet port 85 indicates the first position of piston 83. At its upper end the cylinder 80 has a small outlet port 88.

The piston rod 84 is provided on its end with a clevis 89 for attachment to a time delay lock-out mechanism, and the extension rod 53 is provided with a clevis 90 on its upper end for attachment to a manual operation lever.

Various types of lock-out mechanisms may be employed with this automatic circuit recloser mechanism, provided the lock-out mechanism is such that the contacts may again be closed manually, and provided also that the timing piston 83 is also locked out at the upper limit of its movement. The lock-out mechanism may be housed in the cover of the tank in which the oil is contained, which surrounds the present mechanism.

The operation of the automatic circuit recloser mechanism is as follows: The contacts are closed initially by means of the manual operating lever which is attached to the clevis 90. This lever must be pushed downwardly, whereupon the springs 25 will snap the shield 34 downwardly and move the contacts into closed position. When a surge of current occurs in the circuit in which the device is connected, this current, passing through the coils 11, causes the armature 13 to be drawn upwardly, and the thrust exerted on the armature is in proportion to the amount of current. The more current that is flowing, the greater is the thrust on the armature, and the faster the armature tends to travel.

The more current that is flowing in the coil, the greater the arc between the contacts, and

the faster the piston 17 travels, and ejects oil through the slots 24 at a greater velocity to quench the arc.

As the piston 17 travels upward, the fins 23 carry the springs 25 upward, opening the contacts with a snap action as the shield 34 moves upward, the shield being interposed between the fixed contacts. When the piston 17 reaches the end of its travel beyond the end of slots 24, its travel is arrested by the oil entrapped in the end of the cylindrical chamber 16, and the piston and its associated parts are brought to a quick stop.

The motion of the parts heretofore described is regulated by means of the valves and associated mechanism at the top of the assembly as follows: The bushing 56 is adapted to pump oil from the chamber 91 above it into the conduit 60 and thence past the ball valve 77 into the space below piston 83. The ball valve 77 prevents its return into the conduit 60. Thus a measured amount of oil is pumped into the space below the piston 83 during the initial movement of the armature 13, this pumping action continuing until the cut-off surface 59 of bushing 56 passes the upper side 25 of the conduit 60.

Immediately after the passage 60 is cut off by the bushing 56, the contacts of the switch are opened. Thus a full measure of oil is always forced into the passage 60 and transmitted to the space below the piston 83. The contacts then part, and the rest of the armature travel is utilized to eject oil across the resulting arc. As long as there is an arc, energy is also flowing through the coil 11 which, in turn, pulls the armature with a speed proportional to the current flow. Hence, the greater the arc, the more current that is flowing, the faster the armature travels, and the greater is the oil velocity across the arc path.

After the bushing 56 passes the conduit 60, the shoulder 67 also passes the upper face 69, and oil pressure in the chamber 91 is relieved by passing out of the bore 64 around the tapered portion 66 of the extension rod 53. Prior to this time the opening 64 has been kept closed by the cylindrical portion 65 of rod 53, thus tending to force all of the oil in chamber 91 into the conduit 60.

When the armature 13 is in its raised position the lower cylindrical portion 92 of the extension rod 53 just above the bushing 56 closes the port 64. Thus downward motion of the armature is delayed while the oil seeps into the chamber 91 through the clearances of the shafts in the closed ports and along the armature 13 and armature bushing 56.

The armature extension 53 may not be raised to its extreme upper position by relatively small overloads which are to open the contacts, but it will be raised to that position by the heavier currents. On heavier currents which produce larger arcs at the contacts and higher thrust on the armature, additional time delay will be incurred before the device recloses the contacts. This allows more time for the oil about the contacts to clear itself of gas and carbon.

As the armature 13 passes downward, the cylindrical portion 92 passes out of the port 64, and the tapered portion 66 effects an opening of the port 64 which increases in size as the armature progresses downwardly. Oil may then pass into the chamber 91 around the tapered portion 66 through port 64, but the port 60 is still cut off by the bushing 56.

As the armature 13 progresses downwardly, the cylindrical portion 65 of extension rod 53 closes the port 64, and the bushing 56 opens the port 60.

Thereafter, oil is drawn in by the pumping action of the bushing 56 through the valve port 73, the oil lifting the ball valve 74. The contacts of the switch are not closed until the piston 17 has substantially reached the bottom of its travel. Thus, by properly proportioning the parts, a pre-determined minimum time delay may be introduced on the reclosing of the contacts in any event, and additional time delay is provided when the device has interrupted heavier currents.

Many faults which occur on distribution lines are only temporary, and are cleared automatically by the time delay reclosing of the circuit. In order to vary the amount of time delay during which such faults may be automatically cleared it is desirable to provide for a plurality of instantaneous operations, such as, for example, two openings of the circuit and two time delay closures of the circuit, with a minimum time delay on the reclosing between each contact break and re-make. This sequence of operations should be normally available at any time, regardless of former operations, provided a reasonable time has elapsed since the last operation, such as, for example, fifteen or twenty minutes.

After two or more time delay operations of the switch, each comprising an opening and a reclosing, it is then desirable to introduce a greater time delay, and finally to lock out the switch mechanism in open position if the line disturbance has not cleared itself automatically by that time.

During the first opening of the circuit the timing piston 83 has been moved up to the dotted line position 87. Little resistance is encountered to the escape of oil from the space above the piston 83 at this time, because the oil may pass out of the large escape port 85 as well as the small escape port 88. When the armature 13 returns to its lower position after the first opening operation, the timing piston 83 remains substantially in the dotted line position 87, since the only leakage which is encountered with regard to the space below the piston 83 is that which is incurred by virtue of suitable clearances and leakage past valves.

Thus a measured quantity of oil has been injected into the timing cylinder 80 on the first opening and reclosing of the contacts. This is always a constant amount, regardless of the armature travel, provided the circuit is interrupted, since the contacts do not part until the bushing 56 closes the passage 60 and contact is not re-established until the armature 13 descends by gravity to the bottom of its travel. Therefore, the same volume of oil is pumped into the timing cylinder 80 with each interruption of the circuit, independent of the magnitude of the operation or the intensity of the current, or the viscosity of the oil.

After the first interruption of the circuit, if the overload or short-circuit condition still exists on the power line, and is of the proper magnitude to cause an operation, the armature 13 again rises, unimpeded by the timing cylinder, since the large escape port 85 is still open, and the oil can flow unimpeded into the passage 60.

Thus the second circuit interruption of the device is also a fast opening, and a second measured quantity of oil advances the timing piston 83 to the position indicated by the dash line 86, closing the large outlet port 85 of the timing cylinder.

When the contacts are again closed, the timing piston 83 remains for the short time required

5 to permit a third operation, substantially in the position indicated by the dotted line 86. Upon the occurrence of a third operation immediately following the re-establishing of the contact, the upward travel of the armature 13 is then impeded by the pressure which is established above the timing piston 83 in the timing cylinder 80, since the oil in this chamber can now only escape through the small port 88, plus leakage. If 10 no third operation of the plunger occurs while the timing piston remains in the dotted line position 86, the timing piston 83 will gradually settle downward to the position of Figure 1 by gravity, due to the leakage of oil past the piston and into 15 the apertures 88 and 85.

The size of this small port 88 can be readily proportioned to provide the proper amount of time delay which is desired before the contacts again break the circuit on the third operation and before the armature extension 53 opens the port 64 by raising the reduced portion 66. Thereafter, free travel of the armature 13 is again provided at normal speed to eject oil across the path of the arc, since bushing 56 closes the passage 60 as the port 64 opens up, and the timing cylinder is no longer in the active oil stream propelled by the armature 13.

Thus the present device is able to provide an increased time delay for the opening of the contacts upon the third operation, without, however, preventing the contacts from opening quickly on a snap action, and without preventing the ejection of oil at high speed to quench the arc.

The lock-out mechanism is preferably so adjusted that it is still free to reset the contacts after the third operation, and it may operate a fourth time similar to the third operation, since the port 85 is still closed by the piston 83. Upon the reopening of the circuit a fourth time, the piston 83 raises a suitable spring biased lever 122 on the lock-out mechanism, which is attached to the clevis 89, and this lever engages a suitable mechanism on a linkage attached to the clevis 90, preventing the armature 13 from descending sufficiently to reset the contacts, and also locking the piston 83 in the raised position.

This is a very important feature of the invention, as none of the devices of the prior art with which I am familiar are capable of locking out the time delay condition in the third or fourth position like the present device. Under these conditions, the device can only be placed back in service by a manual operation, which, in this case, consists in tripping the lock-out mechanism so that the armature can move to reset the contacts. When the piston 83 is locked out or latched in its upper position the lower end of the piston 83 has cleared the opening 85, and the port 85 provides a vent for passage of oil which may be pumped into the cylinder 80 under these conditions.

The purpose of holding the piston 83 on lock-out in the fourth position is as follows: When contact is re-established on a line, especially after a prolonged outage, considerable consumer equipment may be connected to the line in the "on" position. The starting currents of these equipments may be sufficient to cause an instantaneous operation of the breaker, but because of the short duration of the surge of current, a time delay would hold the breaker against this transient surge. Thus the time delay which is provided by having the time delay cylinder in its uppermost position prevents the circuit from being broken again unnecessarily, due to a transient

surge of equipment which has been connected to the line in the "on" position.

If, on the other hand, a line fault still exists, the device would operate only once, and again lock out without further damage to the line or without strain on line equipments supplying the power, and with much less wear on the circuit interrupting device, especially the contacts which must bear the brunt of the damaging arcs which are drawn between the contacts.

With the devices of the prior art the timing mechanism resets itself during the lock-out, so that if a line fault still exists when the device is reset manually, the breaker must again go through its full sequence of operations before lock-out. The devices of the prior art frequently operate through one or more of their instantaneous operations upon a manual reset, due to the transient inrush currents which are caused by the switching operation plus the starting currents of the connected load. These operations, caused by transient currents, are avoided by the use of the present invention.

It will thus be observed that I have invented an improved automatic circuit recloser mechanism adapted to provide for a plurality of fast openings of the circuit upon the existence of a fault in the circuit with a time delay closing, and, thereafter, with a time delay opening of the circuit in the third and fourth operations.

Referring to Fig. 3, this is a fragmentary sectional view, similar to Fig. 1, of a modification which includes all of the same elements as Fig. 1, except that the solenoid coil 11 and its armature 13 are arranged lowermost, with the dash pot above the solenoid.

All of the similar parts have been given similar numerals, and the operation of the device is still the same.

The location of the solenoid lowermost in the assembly makes it possible to remove the solenoid coil and substitute another coil to change the rating of the circuit recloser. To do this it is only necessary to remove the lower bolts 100 and the closure cap 101, which is provided with a tubular extension 102 for receiving the armature 13.

This modification also reduces manufacturing costs by simplifying machining and by eliminating the liner tube 57 which extends through the armature coil into the chamber 91, although a tubular sleeve 57 is still employed as a part of the spool on which the coil is mounted.

It is unnecessary to disturb the contact mechanism or any other part of the assembly, except the bolts 100 and cap 101, in removing the coil 11 and substituting another coil.

According to my invention, the greater the current, the faster the armature travels and the faster oil is ejected to quench the arc which is drawn between the contacts. At each opening of the circuit a measured amount of oil is passed into the timing cylinder, independent of the magnitude of the operation or the viscosity of the oil.

In addition to the armature being locked out, the timing mechanism is locked out on the third or the fourth operation, and thus the device is kept in such condition that it will not be actuated again and again, due to the transient surges of current caused by the closing of the circuit and the connection of consumer equipment to the line in the "on" position.

The armature is released from time delay pressure at the instant of contact break to allow the full force of the dash pot piston to eject oil across

the path of the arc, yet the travel of the piston is cushioned and stopped quickly at the end of the dash pot.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. In a circuit maker and breaker, a container, a supply of insulating oil in said container and a switching unit immersed in said oil comprising a support, fixed contact means carried by said support, a movably mounted barrier carrying a movable contact for bridging said contact means, a cylinder carried by the support, said cylinder having a longitudinally extending slot directed toward the space between said fixed contact means, a solenoid, a plunger armature mounted in said solenoid and carrying a piston in said cylinder, said piston acting on the oil in the cylinder as a combined pump and dash-pot and pumping said oil out of said slot between said fixed contact means to extinguish an arc, simultaneously with the interposition of said barrier between said fixed contact means.

2. In a circuit maker and breaker, a container, a supply of insulating oil in said container and a switching unit immersed in said oil comprising a support, fixed contact means carried by said support, a movably mounted barrier carrying a movable contact for bridging said contact means, a cylinder carried by the support, said cylinder having a longitudinally extending slot directed toward the space between said fixed contact means, a solenoid, a plunger armature mounted in said solenoid and carrying a piston in said cylinder, said piston acting on the oil in the cylinder as a combined pump and dash-pot and pumping said oil out of said slot between said fixed contact means to extinguish an arc, simultaneously with the interposition of said barrier between said fixed contact means.

3. In a circuit maker and breaker, a container, a supply of insulating oil in said container and a switching unit immersed in said oil comprising a support, fixed contact means carried by said support, a movably mounted barrier carrying a movable contact for bridging said contact means, a cylinder carried by the support, said cylinder having a longitudinally extending slot directed toward the space between said fixed contact means, a solenoid, a plunger armature mounted in said solenoid and carrying a piston in said cylinder, said piston acting on the oil in the cylinder as a combined pump and dash-pot and pumping said oil out of said slot between said fixed contact means to extinguish an arc, simultaneously with the interposition of said barrier between said fixed contact means, the said barrier being pivotally mounted on said support and being connected to said piston by a spring having its points of connection located so that the line of centers of the spring and its attachment passes the point of pivotal attachment of the barrier to effect a snap action.

4. In a circuit maker and breaker, a container, a supply of insulating oil in said container and a switching unit immersed in said oil comprising a support, fixed contact means carried by said support, a movably mounted barrier carrying a movable contact for bridging said contact means, a cylinder carried by the support, said cylinder having a longitudinally extending slot directed toward the space between said fixed contact means, a solenoid, a plunger armature mounted in said solenoid and carrying a piston in said cylinder, said piston acting on the oil in the cylinder as a combined pump and dash-pot and pumping said oil out of said slot between said fixed contact means to extinguish an arc, simultaneously with the interposition of said barrier between said fixed contact means, the said longitudinally extending slot terminating short of the end of said cylinder so that the oil entrapped in the cylinder beyond said slot cushions the movement of the armature and brings it to a stop.

5. In a circuit maker and breaker, a container, a supply of insulating oil in said container and a switching unit immersed in said oil comprising a support, fixed contact means carried by said support, a movably mounted barrier carrying a movable contact for bridging said contact means, a cylinder carried by the support, said cylinder having a longitudinally extending slot directed toward the space between said fixed contact means, a solenoid, a plunger armature mounted in said solenoid and carrying a piston in said cylinder, said piston acting on the oil in the cylinder as a combined pump and dash-pot and pumping said oil out of said slot between said fixed contact means to extinguish an arc, simultaneously with the interposition of said barrier between said fixed contact means, the said longitudinally extending slot terminating short of the end of said cylinder so that the oil entrapped in the cylinder beyond said slot cushions the movement of the armature and brings it to a stop.

6. In a circuit maker and breaker, a container, a supply of insulating oil in said container and a switching unit immersed in said oil comprising a support, fixed contact means carried by said support, a movably mounted barrier carrying a movable contact for bridging said contact means, a cylinder carried by the support, said cylinder having a longitudinally extending slot directed toward the space between said fixed contact means, a solenoid, a plunger armature mounted in said solenoid and carrying a piston in said cylinder, said piston acting on the oil in the cylinder as a combined pump and dash-pot and pumping said oil out of said slot between said fixed contact means to extinguish an arc, simultaneously with the interposition of said barrier between said fixed contact means, the said longitudinally extending slot terminating short of the end of said cylinder so that the oil entrapped in the cylinder beyond said slot cushions the movement of the armature and brings it to a stop.

7. In a circuit maker and breaker, a container, a supply of insulating oil in said container and a switching unit immersed in said oil comprising a support, fixed contact means carried by said support, a movably mounted barrier carrying a movable contact for bridging said contact means, a cylinder carried by the support, said cylinder having a longitudinally extending slot directed toward the space between said fixed contact means, a solenoid, a plunger armature mounted in said solenoid and carrying a piston in said cylinder, said piston acting on the oil in the cylinder as a combined pump and dash-pot and pumping said oil out of said slot between said fixed contact means to extinguish an arc, simultaneously with the interposition of said barrier between said fixed contact means, the said longitudinally extending slot terminating short of the end of said cylinder so that the oil entrapped in the cylinder beyond said slot cushions the movement of the armature and brings it to a stop.

8. In a circuit maker and breaker, a container, a supply of insulating oil in said container and a switching unit immersed in said oil comprising a support, fixed contact means carried by said support, a movably mounted barrier carrying a movable contact for bridging said contact means, a cylinder carried by the support, said cylinder having a longitudinally extending slot directed toward the space between said fixed contact means, a solenoid, a plunger armature mounted in said solenoid and carrying a piston in said cylinder, said piston acting on the oil in the cylinder as a combined pump and dash-pot and pumping said oil out of said slot between said fixed contact means to extinguish an arc, simultaneously with the interposition of said barrier between said fixed contact means, the said longitudinally extending slot terminating short of the end of said cylinder so that the oil entrapped in the cylinder beyond said slot cushions the movement of the armature and brings it to a stop.

switching unit carried by the container and immersed in said oil, said switching unit comprising a solenoid mounted upon a member having a cylindrical bore, a plunger armature mounted for movement in said bore and including a member slidably mounted in the bore, said plunger armature being mounted upon a rod, a cylinder located axially with said bore, a piston connected to said armature and located in said cylinder to delay the motion of said solenoid for a time interval, depending upon the duration and intensity of a surge of current in said solenoid, contact means controlled by said piston and opened at a predetermined point of the motion of said piston, a time delay cylinder, a pumping cylinder formed by an extension of said bore having a laterally extending conduit leading to said time delay cylinder having a piston, a piston below said conduit on said rod in said pumping cylinder, said latter piston pumping oil into said time delay cylinder until said latter piston passes said conduit and valve means in said conduit for preventing the return of the oil from said time delay cylinder.

5. In a circuit maker and breaker, a container, a supply of insulating oil in said container and a switching unit carried by the container and immersed in said oil, said switching unit comprising a solenoid mounted upon a member having a cylindrical bore, a plunger armature mounted for movement in said bore and including a member slidably mounted in the bore, said plunger armature being mounted upon a rod, a cylinder located axially with said bore, a piston connected to said armature and located in said cylinder to delay the motion of said solenoid for a time interval, depending upon the duration and intensity of a surge of current in said solenoid, contact means controlled by said piston and opened at a predetermined point of the motion of said piston, a time delay cylinder, a pumping cylinder formed by an extension of said bore having a laterally extending conduit leading to said time delay cylinder, a piston below said conduit on said rod in said pumping cylinder, said latter piston pumping oil into said time delay cylinder until said latter piston passes said conduit and valve means in said conduit for preventing the return of the oil from said time delay cylinder, said time delay cylinder having a piston actuated by the oil pumped into said latter cylinder.

6. In a circuit maker and breaker, a container, a supply of insulating oil in said container and a switching unit carried by the container and immersed in said oil, said switching unit comprising a solenoid mounted upon a member having a cylindrical bore, a plunger armature mounted for movement in said bore and including a member slidably mounted in the bore, said plunger armature being mounted upon a rod, a cylinder located axially with said bore, a piston connected to said armature and located in said cylinder to delay the motion of said solenoid for a time interval, depending upon the duration and intensity of a surge of current in said solenoid, contact means controlled by said piston and opened at a predetermined point of the motion of said piston, a time delay cylinder, a pumping cylinder formed by an extension of said bore having a laterally extending conduit leading to said time delay cylinder, a piston below said conduit on said rod in said pumping cylinder, said latter piston pumping oil into said time delay cylinder until said latter piston passes said conduit and valve means in said conduit for preventing the return of the oil from said time delay cylinder.

oil from said time delay cylinder, said time delay cylinder having a piston actuated by the oil pumped into said latter cylinder, said time delay cylinder having an enlarged aperture located above its piston for discharge of oil during the first pumping of oil into said latter piston.

7. In a circuit maker and breaker, a container, a supply of insulating oil in said container and a switching unit carried by the container and immersed in said oil, said switching unit comprising a solenoid mounted upon a member having a cylindrical bore, a plunger armature mounted for movement in said bore and including a member slidably mounted in the bore, said plunger armature being mounted upon a rod, a cylinder located axially with said bore, a piston connected to said armature and located in said cylinder to delay the motion of said solenoid for a time interval, depending upon the duration and intensity of a surge of current in said solenoid, contact means controlled by said piston and opened at a predetermined point of the motion of said piston, a time delay cylinder, a pumping cylinder formed by an extension of said bore having a laterally extending conduit leading to said time delay cylinder, a piston below said conduit on said rod in said pumping cylinder, said latter piston pumping oil into said time delay cylinder until said latter piston passes said conduit and valve means in said conduit for preventing the return of the oil from said time delay cylinder, said time delay cylinder having a piston actuated by the oil pumped into said pumping cylinder, said time delay cylinder having an enlarged aperture located above its piston for discharge of oil during the first pumping of oil into said latter piston, and said time delay cylinder having a second limited discharge opening for discharge of oil from said latter cylinder upon the second pumping of oil into said latter cylinder after its piston has passed the enlarged discharge opening.

8. In a circuit maker and breaker, a container, a supply of insulating oil in said container and a switching unit carried by the container and immersed in said oil, said switching unit comprising a solenoid mounted upon a member having a cylindrical bore, a plunger armature mounted for movement in said bore and including a member slidably mounted in the bore, said plunger armature being mounted upon a rod, a cylinder located axially with said bore, a piston connected to said armature and located in said cylinder to delay the motion of said solenoid for a time interval, depending upon the duration and intensity of a surge of current in said solenoid, contact means controlled by said piston and opened at a predetermined point of the motion of said piston, a time delay cylinder, a pumping cylinder formed by an extension of said bore having a laterally extending conduit leading to said time delay cylinder, a piston below said conduit on said rod in said pumping cylinder, said latter piston pumping oil into said time delay cylinder until said latter piston passes said conduit and valve means in said conduit for preventing the return of the oil from said time delay cylinder, said time delay cylinder having a piston actuated by the oil pumped into said pumping cylinder, said rod extending out of the upper end of said latter cylinder with a sliding fit, and said rod having a reduced portion located to provide an opening around the rod at the upper end of said latter cylinder for discharge of oil when said laterally extending conduit is shut off by said pumping piston.

9. In a circuit maker and breaker with regulated delaying action for its opening or closing, the combination of a solenoid and an armature, said solenoid being connected to receive surges of current on the line and to exert a force on the armature which is dependent on the intensity of the current, a cylinder, a piston in the cylinder connected to said armature, said cylinder and piston acting both as dash-pot and pump, fixed contact means and movable contact means controlled by said armature, said cylinder having an aperture directed toward said contact means to extinguish the arc by discharge of oil from the cylinder, said cylinder and contact means being immersed in oil, a second pump cylinder and a piston connected to said armature and actuated by said solenoid, a time delay cylinder, a conduit extending from said second cylinder to said time delay cylinder having a piston, said second piston pumping oil into said time delay cylinder until it passes said conduit.

10. In a circuit maker and breaker with regulated delaying action for its opening or closing, the combination of a solenoid and an armature, said solenoid being connected to receive surges of current on the line and to exert a force on the armature which is dependent on the intensity of the current, a cylinder, a piston in the cylinder connected to said armature, said cylinder and piston acting both as dash-pot and pump, fixed contact means and movable contact means controlled by said armature, said cylinder having an aperture directed toward said contact means to extinguish the arc by discharge of oil from the cylinder, said cylinder and contact means being immersed in oil, a second pump cylinder and a piston connected to said armature and actuated by said solenoid, a time delay cylinder, a conduit extending from said second cylinder to said time delay cylinder having a piston, said second piston pumping oil into said time delay cylinder until it passes said conduit, said second piston pumping oil into said time delay cylinder until it passes said conduit, said armature being connected to a rod slidably mounted in the end of said second cylinder, said rod having a reduced portion providing a discharge aperture around the rod after said second piston passes said conduit.

11. The combination of fixed and movable contact means with a support, a cylinder carried by said support and having a slot directed toward an arc between said contact means, a piston in said cylinder controlling said movable contact means and acting both as a pump and a dash-pot, said contact means and cylinder being im-

mersed in oil and said piston pumping oil out of said slot toward said contact means, a solenoid having a plunger armature connected to said piston, said solenoid being connected in circuit to actuate its armature responsive to surges of current, said armature being retarded by said piston, a second cylinder and a second piston connected to and actuated by said armature, a third time delay cylinder and a conduit from said second cylinder to said third cylinder, said second piston acting as a pump and pumping oil out of said conduit from its cylinder into said third cylinder, said third cylinder having a piston mounted to be moved by the oil pumped into it.

15. 12. The combination of fixed and movable contact means with a support, a cylinder carried by said support and having a slot directed toward an arc between said contact means, a piston in said cylinder controlling said movable contact means and acting both as a pump and a dash-pot, said contact means and cylinder being immersed in oil and said piston pumping oil out of said slot toward said contact means, a solenoid having a plunger armature connected to said piston, said solenoid being connected in circuit to actuate its armature responsive to surges of current, said armature being retarded by said piston, a second cylinder and a second piston connected to and actuated by said armature, a third time delay cylinder and a conduit from said second cylinder to said third cylinder, said second piston acting as a pump and pumping oil out of said conduit from its cylinder into said third cylinder, said third cylinder having a piston mounted to be moved by the oil pumped into it, said third cylinder having a series of apertures in its side wall for discharging oil from the opposite side of its piston at a rate depending on the position of the piston.

DAVID C. HUBBARD.
